Primary Examiner — Prabhakar Deshmukh(74) *Attorney, Agent, or Firm* — DeLio & Peterson, LLC**CLAIM**

The ornamental design for an “anti-ligature lock,” as shown and described.

DESCRIPTION

FIG. 1 is a perspective view from the left of an “anti-ligature lock” showing our new design. The lock is shown with the handle in an upward position corresponding to an extended latchbolt.

FIG. 2 is a front elevational view thereof. The lock is shown with the handle in an upward position corresponding to an extended latchbolt.

FIG. 3 is also a front elevational view as seen in FIG. 2 except that the lock is shown with the handle partially pivoted down corresponding to a partially retracted latchbolt.

FIG. 4 is a left side elevational view thereof.

FIG. 5 is a right side elevational view thereof.

FIG. 6 is a top side elevational view thereof; and,

FIG. 7 is a bottom side elevational view thereof.

The back surface of the anti-ligature lock is substantially flat for mounting against a door and is not shown. The back surface of the anti-ligature lock forms no part of the claimed design.

The broken lines in the illustrations show environmental structure comprising a door and latchbolt and are not a part of the design sought to be patented.
